CLARENCE L. DAWSON, OF LOS ANGELES, CALIFORNIA.

AUTOMATIC OVERFLOW OUTLET FOR PLUMBING FIXTURES, ETC.

Application filed August 6, 1925. Serial No. 48,479.

To all whom it may concern:

Be it known that I, CLARENCE L. DAWSON, a citizen of the United States, residing at Los Angeles, in the county of Los Angeles and State of California, have invented new and useful Improvements in Automatic Overflow Outlets for Plumbing Fixtures, Etc., of which the following is a specification.

10 This invention particularly pertains to a combined overflow and drain outlet which is especially adapted for use in bath tubs and has as its primary object the provision of a means whereby an overflow and drain outlet may be embodied in a single fitting which may be applied to the ordinary drain outlet of a bath tub or the like and thus eliminate the use of a separate overflow, such as is ordinarily employed in bath tub construction.

20 The invention resides generally in the provision of a fitting adapted to be attached to the drain opening of a bath tub or the like which embodies at least one outlet fitted with a closure member which normally

25 maintains the outlet closed but which is adapted to automatically open under pressure of a predetermined head of water in the bath tub, so as to automatically effect the discharge of excess water from the tub

30 and thereby insure against the tub being filled to overflowing.

The invention further resides in the provision of a means whereby the automatic closure may be manually disposed in an open position to effect drainage of the tub and which is adapted when operated to open said closure to provide an increased outlet to the flow of water through the fitting when draining the tub.

40 The invention resides more specifically in forming the closure of the automatic outlet of a loose sphere or ball supported on an inclined runway and arranged to normally close the outlet or discharge port by gravity

45 in opposition to a head of water and operable to move upwardly on the runway under the influence of a predetermined water pressure to open the discharge port, and adapted on release of pressure to return to the port

50 closing position.

The invention is illustrated in the accompanying drawings, in which:—

Fig. 1 is a view showing the application of the invention;

Fig. 2 is a horizontal section and plan view 55 as seen on the line 2—2 of Fig. 3;

Fig. 3 is a view in vertical section as seen on the line 3—3 of Fig. 2, with parts shown in elevation, illustrating the construction and operation of the combined overflow and 60 drain fitting;

Fig. 4 is a view in perspective of a preferred form of the mounting for the spherical closures;

Fig. 5 is a perspective view illustrating a 65 modified form of the closure mounting.

Referring to the drawings more specifically, 6 indicates a bath tub or the like provided with an outlet 7 in the bottom thereof, and 8 designates generally the outlet control device embodying the present invention, which device includes a shell or casing 9, enclosing a chamber 10 provided with an inlet passage 11 and discharge passage 12. The passages 11 and 12 are formed of nipples 13 and 14, respectively; the nipple 13 being adapted to be screwed into the tub outlet 7 and the nipple 14 being adapted to be connected to the upper end portion 15 of the usual trap leading to a suitable discharge pipe not shown.

In carrying out the invention, the nipple 13 is provided with a tubular extension 16 which projects into the chamber 10 in spaced relation to the side walls of the latter and 85 which extension is formed with one or more ports or outlets 17 in the side walls thereof which open to the chamber 10. The lower end of the extension 16 is provided with a wall 18 formed with an aperture 19 adapted 90 to be closed by a valve 20 carried on an upwardly projecting stem 21 leading through the nipple 13 and fitted at its upper end with a handle 22 here shown as comprising a disc which extends over the upper end portion 95 of the nipple 13 and projects above the tub outlet 7, as shown in Fig. 1.

Mounted in the nipple 13 is a spider 23 through which the stem 21 extends and which affords a bearing in which the stem is 100 turnable and vertically slidable. An upwardly projecting flange 24 is formed on the spider which flange has oppositely inclined top faces 25 and 26 leading upwardly to a notch 27 formed in the upper edge of the flange 24 and extending in radial relation to the axis of the valve stem 21. Projecting from the stem 21 is a pin 28 which is adapt-

ed on turning of the stem in either direction to ride up either of the inclined faces 25 and 26 so as to effect vertical movement of the stem to lift the valve 20 and open the aperture 18; the valve being held in its open position when the pin 28 is seated in the notch 27.

Each port 17 is normally closed from the exterior of the extension 16 by means of a weighted sphere or ball 29 which is supported on an inclined runway A located in the chamber 10 and which sphere is adapted to extend into the port and closely seat on the margin thereof. The inclined runway 15 A preferably comprises a plate or flange 30 provided with a slot 31 as shown in Figs. 3 and 4, which plate is carried by the extension 16; the side margins of the slot 31 forming a track on which the sphere 29 may 20 travel. As a means for preventing the sphere from being unseated from the slot 31 an inclined flange 32 is provided on the extension 16 which flange is spaced from the plate 30 and projects over the 25 sphere 29. The modified form of the runway A shown in Fig. 5, comprises a tube 33 carried by the extension 16 and projecting at an upward incline from the port 17, which tube is formed with a longitudinal slot 34 on its underside forming the track on which the sphere 29 may travel. The 30 spheres being thus mounted on inclined runways leading downwardly toward the ports 17 normally gravitate to closing position. 35 The weight of the spheres 29 together with the opposition to the outward movement thereof afforded by the inclined runways serve to maintain the ports 17 closed against a predetermined head of water in the tub, 40 the pressure of which is imposed on the spheres 29.

The diameter of the valve 20 is such that its outer margin will project beneath the portions of the spheres 29 extending through 45 the ports 17 when the spheres are in their closed positions, as shown in Fig. 3, and the spheres are located in such proximity to the valve 20 that when the latter is moved to its uppermost position as shown in dotted lines 50 in Fig. 3 the margin of the valve will engage the sphere 29 and act to move the spheres outwardly on the inclined runways A to open the ports 17 when the valve 20 is in its fully open position.

55 When the ports 17 and 18 are closed the tub may be filled until the head of water is sufficient to exert such pressure on the spheres 29 as to force the latter outwardly and open the ports 17, thus automatically 60 effecting discharge of excess water from the tub and preventing overflow thereof; the spheres 29 returning to the port-closing position when the water pressure thereon falls to a point insufficient to sustain the spheres 65 29 in their port opening positions. When

it is desired to drain the tub the valve 20 is lifted as before described, thereby opening the aperture 18 and also opening the ports 17 by forcing the spheres 29 outwardly away from the latter.

In order that the spheres 29 will not be caused to open the ports 17 by the force of water discharged from the spigot in filling the tub the hand-hold 22 of the valve stem 21 is designed so that it will extend over the 70 tub outlet and prevent the stream discharged from the spigot from directly entering the nipple 13.

As a means for limiting upward movement of the valve stem 21 a collar 35 is arranged on the latter at such point that when the stem is lifted to position the valve 22 on a plane slightly below the horizontal axes of the spheres 29 the collar 35 will abut against the underside of the spider 23 and thus prevent the valve being lifted to a 80 point above the middle of the spheres.

By providing the arrangement whereby opening the valve 22 will also open the overflow outlets 17 a large discharge area is effected somewhat in excess of the area of the intake of the device.

It is to be understood that the manner of carrying the invention into effect is herein specifically set forth to enable those skilled in the art to make and use the same and is to be considered as illustrative and not in a limiting sense; and that various changes may be made in the parts and in their construction and arrangement within 95 the meaning of the terms and scope of the appended claims without departing from the spirit of the invention.

I claim:—

1. In a combined overflow and drain outlet of the character described, a housing having an inlet and an outlet, a tubular extension leading into the housing from the inlet formed with a side wall port, an inclined runway, a ball closure for said port arranged in said runway adapted to automatically open under the influence of the pressure of liquid delivered to the inlet, and manually operated means extending through said inlet for opening said closure.

2. In a combined overflow and drain outlet of the character described, a housing having an inlet passage and an outlet passage, a tubular extension leading from the inlet passage into said housing formed with a side wall port, a weighted sphere normally closing said port from the exterior of said extension, an inclined guide-way supporting said sphere, and means operable from the exterior of said housing through said inlet passage for moving said sphere up said inclined guideway to its port opening position.

3. In a combined overflow and drain outlet of the character described, a housing

- having an inlet passage and an outlet passage, a tubular extension leading from the inlet passage into said housing having an end wall formed with an aperture, a valve 5 for closing said aperture, a stem on said valve projecting upwardly through the inlet passage, said extension being provided with at least one side wall port, a gravity operated closure normally closing said port 10 adapted to open outwardly under pressure of a head of liquid directed thereagainst from the interior of said tubular extension, and said closure being adapted to be opened by lifting said valve to its open position.
- 15 4. In a combined overflow and drain outlet of the character described, a housing having an inlet passage and an outlet passage, a tubular extension leading from the inlet passage into the interior of said housing having a plurality of side wall ports, inclined runways leading upwardly from said ports exteriorly of said tubular extension, weighted spheres supported on said runways normally closing said ports and adapted to be moved outwardly and upwardly on said guideways under the influence 20 of fluid pressure directed thereagainst from the interior of said tubular extension, and manually operable means for collectively disposing said spheres in their port-opening positions.
- 25 5. In a combined overflow and drain outlet of the character described, a housing having an inlet passage and an outlet passage, a tubular extension leading from the inlet passage into the interior of said housing having a plurality of side wall ports, inclined runways leading upwardly from said ports exteriorly of said tubular extension, 30 weighted spheres supported on said runways normally closing said ports and adapted to be moved outwardly and upwardly on said runways under the influence of fluid pressure directed thereagainst from the interior of said tubular extension, said tubular extension being formed with an end aperture, a reciprocal valve for closing said aperture, a stem on said valve projecting upwardly through the inlet passage, said valve being adapted on being elevated to 35 collectively move said spheres outwardly to their port-opening positions.
- 35 6. In a combined overflow and drain outlet of the character described, a housing having an inlet passage and an outlet passage, a tubular extension leading from the inlet passage into the interior of said housing having a plurality of side wall ports, inclined runways leading upwardly from said ports exteriorly of said tubular extension, weighted spheres supported on said runways normally closing said ports and adapted to be moved outwardly and upwardly on said runways under the influence 40 of fluid pressure directed thereagainst from the interior of said tubular extension, said tubular extension being formed with an end aperture, a reciprocal valve for closing said aperture, a stem on said valve projecting upwardly through the inlet passage, said valve being adapted on being elevated to 45 collectively move said spheres outwardly to their port-opening positions.
- 45 7. In a combined overflow and drain outlet of the character described, a housing having an inlet and an outlet passage, a tubular extension leading from the inlet passage into the housing having an end wall formed with an aperture, a valve for closing said aperture, a stem on said valve extending upwardly through the inlet passage, means whereby turning said stem will lift said valve, said tubular extension being formed with a plurality of side wall ports, and weighted spheres normally seating on the margins of said ports arranged exteriorly of the tubular extension and projecting through said ports into the path of travel of said valve, whereby on lifting said valve said spheres will be moved outwardly 50 collectively to open said ports.

In testimony whereof I have affixed my signature.

CLARENCE L. DAWSON.
